UNITED STATES PATENT OFFICE.

WARREN H. TAYLOR, OF STAMFORD, CONNECTICUT, ASSIGNOR TO THE
YALE & TOWNE MANUFACTURING COMPANY, OF SAME PLACE.

DESIGN FOR A LOCK-BOX DOOR.

SPECIFICATION forming part of Design No. 23,941, dated January 1, 1895.

Application filed November 27, 1894. Serial No. 530,186. Term of patent 14 years.

To all whom it may concern:

Be it known that I, WARREN H. TAYLOR, a citizen of the United States, and a resident of Stamford, in the county of Fairfield and State of Connecticut, have invented and produced a new and original Design for a Lock-Box Door, of which the following is a specification, reference being had to the accompanying drawing, showing a front view thereof.

5 The leading features of my design consist in a panel of radiating lines or rays forming a back-ground, the representation of an eagle on the back-ground, having a shield located on its breast, and a frame surrounding the

10 panel.

15

1 represents the door of a lock-box. 2 represents the frame thereof containing a panel 3 of radiating lines or rays.

4 represents an eagle having partly spread wings and a shield 5 located on its breast. 20

Having thus described my invention, the following is what I claim as new therein and desire to secure by Design Letters Patent:

The design for a lock-box door substantially as herein shown and described.

WARREN H. TAYLOR.
